INVENTOR:
HERBERT HASTINGS

BY
Frank Reiber
ATTORNEYS.

UNITED STATES PATENT OFFICE.

HERBERT HASTINGS, OF ROCHESTER, NEW YORK.

OIL GAUGE.

Application filed March 11, 1920. Serial No. 365,044.

To all whom it may concern:

Be it known that I, HERBERT HASTINGS, a citizen of the United States, residing at Rochester, in the county of Monroe and State of New York, have invented certain new and useful Improvements in Oil Gauges, of which the following is a specification.

The object of this invention is to provide a new and improved form of oil gauge.

This and other objects of the invention will be fully illustrated in the drawings, described in the specification and pointed out in the claims at the end thereof.

In the drawings,

Figure 1 is a perspective view of an oil gauge containing my invention.

Figure 1A is a section on the line 1AX—1AX of Figure 2.

Figure 2 is a top plan view of the oil gauge as placed in the tank.

Figure 3 is a bottom plan view of the gauge with the cover and dial removed.

Figure 4 is a vertical section on the line 4X—4X of Figure 2.

Figure 5 is a side elevation of one of the cams formed in the side of the cap.

In the drawings, like reference numerals indicate like parts.

In the drawings, reference numeral 1 indicates the float of the gauge guided by the guide rods 2 and 3 which are joined together by the yoke 4 at the bottom. The float is grooved on the sides as indicated at 5 and 6 and is bound around the opening by a strap 7, which strap has a forked end at 8 that engages with the guide 3. The tongue which is struck down from the fork engages with the float at 9 and the other end of the strap engages with the float at 10. The float

and strap are perforated to engage with the square rod 11, which rod is twisted spirally on itself so that as the float rises and falls thereon, the square rod 11 will be turned thereby, the float being held against rotation by the guide rods 2 and 3. The upper ends of the guide rods are rigidly fastened in the cover 12 which is cup shaped in the middle, the depression being round in outline. In this depression the guide rods are fastened. The square rod 11 has its lower end turned round as indicated at 13 and is mounted to rotate in the yoke 4 in the bottom. At the top it passes thru the cover 12 in which it is mounted to rotate and on its upper end carries the pointer 14 which

the purpose of indicating the extent to which the tank is full or empty as the float rises or falls in the tank. The margin of the cup 12 is surrounded by the web 15 which is octagonal in shape and from which extends downwardly the flange 16 which is also octagonal in shape so that a wrench can be applied thereto for the purpose of turning it. In the cup shaped depression of the cover is carried the reading dial 17, a spacing ring 18, a round glass plate 19, a washer 20 and a locking ring 21, by which the parts are held in place and a water or oil tight joint is secured. The sides of the cup shaped portion of the cover are struck out at intervals about 120° apart to form cam shaped lugs 22, each of which has a locking depression 23 therein. The depressions 23 in the cam surfaces of the cam lugs 22 form shoulders 23A near the end of these cam surfaces as illustrated in Figures 1A and 5.

For the purpose of fastening the oil gauge in the tank, I provide the flanged collar 30, in which 31 indicates the collar and 32 indicates the outside flange having openings therein by which it is fastened to the tank by screws and rivets. Inside of the collar is the inside flange 33 which is recessed at 34, 35 and 36 to receive the lugs struck up in the cup shaped part of the cap. When the flanged collar 30 is fastened on the tank the float and guides are passed thru the opening in the collar and the lugs 22 pass down into the recesses 34, 35 and 36 until the cams on the lugs 22 can engage under the inner flange 33 at these recesses. By turning the cap on its vertical axis the inside flange is forced up on the cams until a further movement of it is arrested by the shoulder 23A and this locks it sufficiently against movement as illustrated in Figure 1A. The cap is moved to this position by putting a wrench thereon and forcibly turning it and can be moved back to its starting point in the same manner when it is desired to remove the gauge.

I claim:

1. In a gauge, the combination of a flanged collar having a series of recesses on the inside thereof, a head having a cup shaped depression capable of engaging in said collar, lugs formed on the outside of the side of said cup shaped depression, said lugs having cam shaped surfaces on the top thereof, said lugs being capable of passing into said recesses and engaging under the

flange of said collar at the side of said recesses.

2. In a gauge, the combination of a head having a cup shaped depression therein, lugs formed on the outside of the side of said cup shaped depression, said lugs each having a cam on the top thereof, means with which said cams can engage on the rotation of said head to lock the head in place.

3. In a gauge, the combination of a head having a cup shaped depression therein, lugs formed on the outside of the side of said depression, said lugs each having a cam on the top thereof, a web surrounding the rim of said depression and a flange on said web.

4. In a gauge, the combination of a head having a cup shaped depression therein, lugs

formed on the outside of the side of said depression, said lugs each having a cam on the top thereof, a web surrounding the rim of said depression, and a flange on said web, said flange having flat sides.

5. In a gauge, the combination of a head having a cup shaped depression therein, lugs formed on the outside of the side of said cup shaped depression, said lugs each having a cam on the top thereof, means with which said cams can engage on the rotation of said head to lock the head in place, said cams each having a depression therein to form a stop for said engaging means.

In testimony whereof I affix my signature.

HERBERT HASTINGS.
